SCREEN REPAIR DEVICE

Clarence Gronberg, Elgin, Ill., assignor to Arnold B. Carlson, Aurora, Ill.

Application October 16, 1939, Serial No. 299,645

4 Claims. (Cl. 140—3)

This invention relates to screen repair units and their method of construction and more particularly to improved screen patch attaching expedients for repairing punctured or frayed wire screens, although certain features thereof may be employed with equal advantage for other purposes.

It contemplates more especially the provision of an improved wire screen patch that is neat, compact, rugged in construction, and readily applicable for efficient and practical attachment over a defective region of a screen without entailing any appreciable time or labor.

One object of the present invention is to provide a simple, rugged screen patch of improved construction.

Still another object is to provide an improved screen repair device having spaced securing means associated therewith for superimposed merger with a frayed or punctured wire mesh screen.

A still further object is to provide an improved screen repair device which may be readily and conveniently superimposed on a punctured, frayed or torn wire mesh screen to serve as a substantially integral and closely adherent patch therefor.

Other objects and advantages will appear from the following description of an illustrative embodiment of the present invention.

In the drawing:

Figure 1 is a fragmentary sectional front view in elevation showing the placement of ductile pellets and wire mesh screening in the die members prior to the formation of the finished screen repair device.

Figure 2 is the same view as Figure 1 showing the simultaneous formation of securing means and their incorporation with the wire screening.

Figure 3 is a bottom plan view of the finished screen repair device embodying features of the present invention.

Figure 4 is a top plan view of an enlarged fragmentary section of the device shown in Figure 3, illustrating the bond formed between the wire screening and the securing element.

Figure 5 is an enlarged fragmentary view in front elevation of one of the securing elements shown in Figure 3.

Figure 6 is a front elevation view illustrating the method of fastening a screen repair device of the character described to a confronting wire screen.

Figure 7 is a top plan view of a wire screen

to which a screen repair patch has been applied in accordance with the teachings of the present invention.

The structure selected for illustration comprises a metallic meshed screen 10 formed by interweaving a plurality of thin, flexible transverse wires 11, which are spaced to present a screen mesh sheet preferably though not essentially corresponding to the common type of wire screening in commercial use. In order that the screen strip 10 may serve to reinforce and cover a punctured, torn or frayed wire screen 12 to form a substantially integral and/or permanent part thereof, a plurality of metallic securing elements or fasteners, in this instance ductile pellets 13, are imbedded at spaced intervals in the screen strip 10.

The fasteners 13 that are preferably though not essentially formed from a spherical pellet 14 such as lead or other suitable ductile metal essentially characterized by its soft, ductile qualities, have a substantially circular base 15 with a frusto-conical lug 16 projecting for a short distance therefrom. It should be noted that the fastener base 15 must be of greater width and area than the corresponding dimensions of any one of the minute spaces 17 in the meshed screen 10. Thus, fasteners 13 will be securely attached to said screen by imbedding a single mesh of wires 11 in fastener base 15 (see Figure 4). This method of securing the fasteners 13 with the wire screen 10 to be more fully described hereinafter, is accomplished by the application of pressure in such a manner that said fasteners are each intimately interlocked and bonded within a single mesh 17 so that they cannot be readily torn from said screen.

The completed screen repair strips 10, ready for commercial use, are produced by placing a plurality of ductile spherical pellets 14 in an equal number of forming dies 18 having substantially frusto-conical cavities 19 in the upper extremities 20 thereof wherein said pellets are retained. The forming dies 18, in this instance, are shaped from elongated cylindrical rods 21 of hardened steel or other suitable die material, and are slidably mounted within vertical guide bores 22 provided therefor in the lower stationary plate 23 of die press 24. Driving mechanism (not shown), which is controlled by an attendant through suitable lever means (not shown), is provided for reciprocally actuating plunger rods 21 within predetermined limit positions.

The forming operation is commenced by countersinking the forming dies 18 until the upper

edges 20 thereof are sufficiently below the flat surface 25 of stationary plate 23 so that the spherical pellets 14 when placed in said dies, will be substantially level with said surface 25. As shown, the next step comprises the feeding of a strip of wire screening 10 into the die press 24 so as to cover the soft, workable pellets 14. Then the attendant operating the die press 24 shifts the proper pedal or lever control and the forming dies 18 move upward for some distance beyond the plate surface 25 to be confronted by the downward moving of platen 26 simultaneously set in motion. The pellets 14 and wire screening 10 are then subjected to sufficient pressure between the cooperating platen 26 and forming dies 18 to shape said pellets into the previously described fasteners 13, and at the same time securely imbed said fasteners in the individual meshed areas 17 of said screening to produce the device constituting the present invention.

It should be apparent that a plurality of forming dies 18 are spaced at predetermined intervals in the stationary plate member 23 to imbed or flow a plurality of correspondingly spaced fasteners 13 preferably of ductile metal in the comparatively small strips of screen 10, the strips 10 being produced after cutting larger sheets of wire screen into small, convenient size patches and feeding them through the die press 24. A plurality of said patches 10 may then be confined in a container to provide a convenient, inexpensive and saleable screen repair kit for repairing and reinforcing any punctured, torn, rusted or frayed screen 12 (Figure 7) such as commonly used for doors and windows.

When the screen patch 10 is to be applied to a wire screen 12 requiring the necessary aforementioned repairs, a proper sized patch is first selected from the repair kit, or if not available in a kit, then cut to size from a larger sheet so as to effectively cover the damaged portion of said screen. Having provided a suitable supporting surface (not shown) for the damaged part of said screen, the patch 10 is applied so that the projecting fastener lugs 16 will engage the confronting mesh screen. Because of the soft, ductile character of the fasteners 13, they may be readily pressed or hammered into the wire screen 12 in such a manner as to cause the frusto-conical fastener lugs 16 to project into the spaces 17 between the wires 11 forming said screen.

When the screen is well supported on one side, while the fasteners 13 are pressed or hammered into the screen from the opposite side, the lugs 16 projecting between wires 11 will be spread so as to cause said wires to be securely imbedded

therein, thereby forming a closely and intimately interlocked bond between the patch 10 and the screen 12, so that the two become substantially integral and closely adherent (see Figure 6). It is worthy of note that the ductile fasteners 13 function substantially as a soft metal weld between two similar sheets of metal screen and a closely adherent, tightly secured bond is thus established therebetween.

With the teachings of the present invention, an improved, simple screen repair device is provided which serves as an effective, inexpensive screen patch to be readily applied to any punctured, torn, rusted or frayed screen. Because of its simplicity, effectiveness and low cost, it answers the screen repair problem in every community and results in a neat, permanent patch which will substantially add to the life of the wire mesh screen.

Various changes may be made in the embodiment of the invention herein specifically described without departing from the invention or sacrificing any of the advantages or features thereof, and nothing herein shall be construed as limitations upon the invention, its concept or structural embodiment as to the whole or any part thereof, except as defined in the appended claims.

I claim:

1. In a device of the character described, the combination with a wire screen strip, of spaced ductile pellet fastener means partially imbedded in said screen strip proximate to the edge and intermediate the ends thereof for engagement with a similar confronting wire screen.
2. In a device of the character described, the combination with a wire screen strip, of a plurality of spaced ductile pellet fastener means partially imbedded in said screen strip intermediate the ends thereof for engagement with a similar confronting wire screen.
3. In a device of the character described, the combination with a wire screen strip, of a plurality of spaced ductile pellet fastener means partially imbedded in said screen strip intermediate the ends thereof, said ductile pellet fastener means having a projecting element for engagement with a similar confronting wire screen.
4. In a device of the character described, the combination with a wire screen strip, of a plurality of spaced ductile pellet fastener means partially imbedded in said screen strip intermediate the ends thereof, said ductile pellet fastener means having an integrally formed projection for intimate interlocking engagement with a similar confronting wire screen.

CLARENCE GRONBERG.
